UNITED STATES PATENT OFFICE.

JNO. STEVENS, OF NEW YORK, N. Y.

SHIRT-BOSOM FOLDER.

Specification forming part of Letters Patent No. 22,039, dated November 9, 1858; Reissued October 24, 1865, No. 2,097.

To all whom it may concern:

Be it known that I, JOHN STEVENS, of New York, in the county of New York and State of New York, have invented new and 5 useful Improvements in Shirt-Bosom Fold-ers, the construction and operation of which I have described in the following specification and illustrated in the accompanying drawings with sufficient clearness to enable 10 competent and skilful workmen in the arts to which it pertains or is most nearly allied to make and use my invention.

My said invention consists in the arrangement of a series of strips of metal made of 15 equal lengths and width with a number of pins secured in a slot in angle irons attached to the ends of the bed plate, and there secured by a nut on the under side. The angle irons being graduated admit of a ready ad- 20 justment of the pins to any distance apart the distance being equal to the width of the plaits desired in the bosom.

In the accompanying drawings my invention is represented as follows: 25 Figure 1, is a plan showing the linen folded between the tins. Fig. 2, is a front elevation. Fig. 3, is a side elevation. Fig. 4, is a side elevation showing the tins with a flange on one edge by which they are made 30 to lie parallel.

A is a bed plate made of wood. Secured to each end of the bed plate and of nearly the same length are two angle irons B B having a slot running lengthwise of the 35 angle irons made to correspond with the T head of the pins.

C are pins having a square head forming a shoulder near the bottom with a screw thread and nut beneath by which the pins 40 are securely held in place.

D are strips of metal about an inch wide and nearly the length of the bed plate, the ends of which are cut away so as to leave an ear b on each end having an eye a, the pins 45 passing through which hold the tins D in place. Tins have been used before in bosom folders, but the great difficulty has been in making small plaits. The tins being made the width of the plaits made them so slender

50 that they were liable to spring, thereby leaving the plaits crooked, which in my machine is avoided as the small plaits are made with the same size tins as the large ones.

The surface of the angle irons is gradu- 55 ated so that the plaits can be easily measured by moving the pins in the slot; also when the linen is a little short the plaits can be made narrower to accommodate the linen.

E E are two lifters rabbeted into the bed plate near the ends, and made a little longer 60 than the width of the bed plate; these lifters are for the purpose of raising the tins off of the pins after the bosom has been folded. In folding I use six thicknesses of linen at once.

In order to have the tins lie level as in 65 Fig. 4, I make a flange on the opposite edge of the tin to where the ears are, on half of the number of tins the thickness of one tin. On the other half or remainder, the tins be- 70 ing numbered, the first one has a flange the thickness of one tin, the second of two tins, the third three, and so on.

The operation is as follows: Place the 75 linen on the bed bottom and lay the first tin on it, allowing the linen to overlap the tin enough to allow for stitching; the next tin is then put on and the linen turned over the edge the nearest to where the tin is slipped over the pin. For all of the narrow plaits two tins on each pin are required in oppo- 80 site direction, and for the wide plaits only one tin. I get the narrow plait with the wide tin by turning the tins. The tins are laid on one at a time, and the linen turned over until all are on. Then the tins are 85 taken from the pins by raising the lifters up, the tins being then drawn out, the bosom is ready for stitching and the machine ready for more.

The particular improvement which consti- 90 tutes my said invention and which I claim as having been originally and first invented by me is—

The combination of a series of tins made as described with a series of pins arranged 95 in a slot in the angle irons attached to the bed plate, the pins being adjustable by means of which the plaits can be made of any desired width without different sizes of tins with the lifters for raising the tins from 100 the pins, the whole being arranged as described for the purposes set forth.

JOHN STEVENS.
